UNITED STATES PATENT OFFICE.

LE GRAND L. CLARK, OF NEW YORK, N. Y., ASSIGNOR OF ONE-HALF TO THE SHERIDAN IRON WORKS, A CORPORATION OF NEW YORK, AND ONE-HALF TO T. W. & C. B. SHERIDAN COMPANY, A CORPORATION OF NEW YORK.

DETECTOR-CONTROLLED GLUING MECHANISM.

1,392,117.

Specification of Letters Patent. Patented Sept. 27, 1921.

Application filed November 14, 1919. Serial No. 338,021.

To all whom it may concern:

Be it known that I, LE GRAND L. CLARK, a citizen of the United States, residing at New York, in the county of New York and State of New York, have invented certain new and useful Improvements in Detector-Controlled Gluing Mechanism, of which the following is a specification, reference being had therein to the accompanying drawing.

10 This invention is a novel detector controlled gluing mechanism, and the principles of the invention are herein shown applied to a machine for gluing together the component parts of books or pamphlets, for example, for gluing the exterior paper sheet or cover in place, although the principles could be used on analogous machines for treating similar articles for example, for gluing together two sheets of paper, constituting a newspaper or folder, rather than a book or pamphlet.

As indicated by the title of this invention, its main object is to provide a gluing mechanism controlled by a detector, so that on the absence of one of the component parts, for example, when a sheet is missing and fails to be fed, this will operate to prevent the application of glue, and therefore to prevent the mechanical parts of the machine becoming smeared with glue, which would quickly render the machine unfit for practical use. I will show the invention applied to the general type of bookbinding or covering machine shown in Bredenberg Patents 1,073,324 and 1,248,252. In these patents the successive books are carried along a horizontal path in a train or procession advancing to the various mechanisms, including the gluing mechanism and the cover sheet applying mechanism. The book is held with its back downwardly, and the glue is applied at the lower or back edge, and subsequently the cover is applied at the same point on the book. In the last mentioned patent the glue applying device is bodily dropped at the end of each book or gluing operation and lifted for the next one. The earlier patent of Hull 534,219 likewise employed the plan of dropping and raising the glue roll.

I do not herein claim to be the first to employ a detector, with connecting mechanism, for preventing the application of glue when a sheet or analogous object fails to be

fed, and indeed the prior patent of Bascom No. 551,918 shows such a mechanism, the broad principles of which are applicable to the present purposes. It is an object of the present invention to afford a detector controlled gluing mechanism of the same general nature as that of Bascom, but specifically improved and adapted to the uses herein disclosed. Other objects and advantages of the present invention will appear in the hereinafter following description of one form or embodiment thereof, or will be understood to those skilled in the art.

To the accomplishment of such objects and advantages, the present invention consists in the novel detector controlled gluing mechanism and the novel features of combination, construction, arrangement and detail herein shown, described or claimed.

Figure 1 of the drawings may be considered as a more or less diagrammatic side elevation of a machine for gluing covers to books, embodying the principles of the present invention.

Fig. 2 is a partial right elevation of the detector and associated parts.

Along fixed guides 5 travels an endless train of clamps 6, each of which holds a book B with the back edge of the book downwardly. Each book, after passing from any preliminary treatments, comes next to the gluing mechanism shown at the left, and then to the cover applying mechanism at the right of the figure of the drawings. The gluing mechanism applies glue to the back of each book, and the covering mechanism thereupon applies a cover. A succession of paper sheets or covers C, C, C, C, is shown, coming from any suitable cover supply, such as the well known paper feeder. Each cover passes upwardly toward the path of the books, between lower and upper tapes 7 and 8, and these tapes near the top throw the cover onto a platen or reciprocating table 9, which receives the covers one at a time, and rising applies them to the glued backs of the books, in a manner more fully described in said prior Patent 1,248,252.

The glue applying device comprises a glue roll 10, driven by a belt 11, and running in the glue within a vessel 12. When elevated the gluing device is in such position that the book moves along over the rotating roll and receives glue along its length. Instead

of these parts being fixed in position, the glue vessel is here shown mounted to move up and down, for example, about a pivot 13. The means for moving it down and up is 5 associated with and will be described in connection with the detector and detector controlled mechanism.

The mechanism hereof comprises the glue applying device, adapted to rise to the point 10 where the glue is to be applied, and to descend to an inoperative position, in combination with a yielding means such as a spring or a counterweight or the like, tending always to overbalance or lift the glue device to its operative position, timed connections, such as a cam, acting after each 15 gluing operation for causing the glue device to descend to its inoperative position, and then allowing it to rise for the next operation, a normally inoperative lock device adapted to act at the time when the gluing device is in its lowered position, for holding it down against the lifting tendency of the spring or counterweight, and together with 20 these elements detector-controlled connections adapted for rendering operative the lock device, and thereby preventing any given gluing operation, all without stopping the machine.

30 The free or movable end of the glue vessel rests upon a connection or stud 14, which has a head 15 co-operating with a fixed frame part 16 to form a stop limiting the downward movement of the vessel. The connection 35 14 in turn rests upon the rightward arm 17 of a lever, having also leftward arm 18 and upward arm 19. The connection 14 acts substantially as a link between the vessel 12 and lever arm 17, the weight of the 40 vessel being such that the connection is substantially positive, the parts always moving up and down in absolute unison.

As a yielding means tending to lift the glue device to its operative position, I prefer a spring 20, although a counterweight indicated at 21 might be employed. The 45 spring is preferably arranged to pull down on the leftward lever arm 18, although obviously it could pull up on the rightward arm 17 or leftward on the upward arm 19 to the same effect, namely, to overbalance the glue device, giving it a tendency to rise. The limit of upward movement may be determined by a suitable stop, for example, 50 by the dwell portion of the cam to be described.

The parts thus described normally hold the gluing device in elevated or operative position. In order to cause the glue device 55 to descend periodically, I provide timed connections which may take various forms, but are shown as including one of the operating shafts 22 of the machine, the same carrying a cam 23 having an active portion 60 24 and a dwell 25, so arranged as to co-

operate with the roller 26 on the upward lever arm 19. The cam portion 24 thrusts the lever to the right, thus overcoming the resistance of the spring 20, and in effect forcing downward the glue vessel. The 70 contour of the cam is such as to allow the spring to again act and lift the glue vessel. The cam dwell 25 acts as a stop, limiting the rise of the glue vessel so that it cannot rise substantially above the level necessary for 75 gluing the book. The shaft 22 is driven in time with the remainder of the machine, making, for instance, one rotation for the advance of each book, and the cam is timed on the shaft so as to thrust down the glue 80 device at the completion of the operation of gluing one book, and to allow it to rise for the next book or operation. The cam does not act to force the glue device up. This is left solely to the yielding means, spring 85 or counterweight.

The parts as thus far described would operate to apply glue to each book, the glue vessel lowering between operations. It will be perceived that, when the glue vessel is 90 in its lower position, it is possible to lock or hold it there, since there is no positive or cam lifting action. In order, therefore, to prevent any given gluing operation, I provide a lock device consisting of a hooked arm 95 27, pivoted at 28 on a low portion of the machine frame, and having a hook 29 at its upper end, normally inoperative, but adapted to swing over the lug or stud 30 on the lever arm 17. These parts might be relatively differently arranged, so long as when 100 operated they serve to hold the three-armed lever, and therefore, the glue device, in the inoperative position shown.

It only remains to control the lock device 105 27 by the fed sheets or covers. This is herein accomplished by means of a swinging detector 31, pivoted at 32, and pulled upon lightly by a spring 33, so as to bear against the left or underside of the ascending sheets. 110 As long as a proper succession of sheets continues, the detector 31 will always be held in the position shown in the drawings. But if, by chance, a sheet is missing, the detector 31 is permitted to swing to the right under 115 the influence of the spring 33. A simple link 34 transmits this motion to the hook or lock 27, which it will be noticed is delicately poised. The result is that, when a sheet is missing, the lock is swung from its shown 120 position toward the right, so that, when the glue device is lowered and inoperative, the hook 29 may swing over the lug 30, and thus lock the parts in inoperative position. The cam 23 will make a complete rotation with 125 the follower 26 held wholly away from the cam until the active cam portion 24 again comes to position. It will then contact the roller 26 and slightly displace the parts sufficiently to separate the hook 29 and lug 30 130

to a degree to permit the former to readily swing to the left as the detector 31 is swung to the left with the coming along of the next sheet of paper. In this way, by simple and 5 easily maintained mechanism, the application of glue is prevented when the sheet is missing and the smearing of glue upon the platen 9 and other parts of the machine will be prevented.

- 10 I believe it new herein to provide an overbalanced glue device or vessel, its tendency to rise being limited, together with an automatic means to depress the vessel after each gluing operation, and a hook or lock to hold 15 it down on certain occasions to prevent one or more gluing operations.

It will thus be seen that I have described a detector controlled gluing mechanism embodying the principles of the present invention, but since many matters of design, arrangement, combination and detail may be variously modified without departing from the principles, it is not intended to limit the 20 invention to such matters except so far as 25 specified in the appended claims.

What is claimed is:

1. In combination, means for conveying books or analogous articles with the under surface thereof exposed, means for applying 30 covers or sheets to the exposed under surfaces of the articles, means for conducting the sheets successively to the point of application, a glue applying device adapted to apply glue to the under side of each article 35 before the application of a sheet thereto, the same adapted to rise to the article to be glued and to descend to an inoperative position, a yielding means tending to lift the glue device to operative position, timed connections acting after each gluing operation

for causing the glue device to descend to inoperative position and allowing it to rise for the next operation, a normally inoperative lock device adapted to act when the gluing device is in its lowered position for 45 holding it down against the lifting tendency of said yielding means, and detector-actuated connections, controlled by the presence of the sheets in said sheet conducting means, adapted for rendering operative said lock 50 device, and thereby preventing the application of glue to the article when the corresponding sheet is missing, without stopping the machine.

2. In combination, means for conveying 55 books or analogous articles with the under surface thereof exposed, means for applying covers or sheets to the exposed under surfaces of the articles, means for conducting the sheets successively to the point of application, a glue applying device adapted to apply glue to the under side of each article before the application of a sheet thereto, the same being overbalanced to give it a tendency 60 to rise to the article to be glued but 65 permitting it to be lowered to an inoperative position, a timed actuator acting after each gluing operation for causing the glue device to descend to inoperative position and allowing it to rise for the next operation, a lock 70 member adapted to operate when the gluing device is in its lowered position for holding it down against its lifting tendency, and sheet-controlled connections adapted for rendering operative said lock device and 75 thereby preventing gluing when the sheet is missing.

In testimony whereof, I have affixed my signature hereto.

LE GRAND L. CLARK.
